TEMPORARY SECURING DEVICE

Emmett F. Kennedy, Maple Heights, Ohio, assignor to Grand Industries, Inc., Cleveland, Ohio, a corporation of Ohio

Application December 3, 1949, Serial No. 131,037

6 Claims. (Cl. 292—288)

1

This invention relates to a fastening device for temporarily securing doors, drawer fronts, and other outwardly movable panels of cabinet structures such as domestic cooking ranges, washers, radios, furniture, and the like against accidental opening or outward movement or displacement during shipment, and particularly to a readily attachable and detachable fastening device for securing the doors and drawers of the vitreous enamelled metal cabinets of domestic gas cooking ranges securely in closed position during shipment thereof. The invention is described hereinafter as applied to doors and drawers of domestic gas range cabinet structures, its application to other cabinet structures and to closure panels other than doors and drawer fronts being apparent from the illustrative example.

Heretofore in the shipment of domestic gas cooking ranges the practice has been to secure the doors and drawers in closed position by the use of adhesive tape. Usually such tape is installed, one strip above the door or drawer handle and one strip immediately therebeneath, the strips extending across the front face of the door and range and for a substantial distance along the side walls of the range. Considerable expense is involved in securing the doors and drawers in this manner due to the cost of the tape and the time required for installation. Furthermore such tape strips cannot be relied upon to remain securely in place, particularly in damp weather, inasmuch as the adhesive tends to soften and come loose. Also, if the range is shipped with the doors secured in this manner, the recipient is put to considerable trouble to remove not only the tape but the residual adhesive film remaining on the walls of the range and the collected dirt and foreign matter that adheres to the range because of the residual adhesive film. Though such ranges are shipped in very rigid and close fitting crates, no other equally satisfactory manner of fastening the doors and drawers has heretofore been found. If, instead of using tape, bracing is interposed between the doors and the side of the crate, great care must be exercised to prevent direct transmission to the door or drawer of any shocks imparted to the crate. Likewise, the crating materials are apt to damage or mar the external finish of the range by rubbing thereagainst. Furthermore such bracing is very costly because of the material required and labor involved.

It is necessary, however, that such doors and drawers be held securely and substantially without any play or looseness. Since they are relatively heavy, any movement thereof results in severe impact shocks when their movement is arrested suddenly by other parts of the range and such impact shocks are apt to be transferred throughout the range and crack, chip or other-

2

wise damage the vitreous enamelled finish not only of the doors and drawer fronts but also of other parts of the range.

Damage in shipment of gas ranges resulting from slamming and banging of the doors and drawers during shipment is extremely high.

The object of the present invention is to provide a simple inexpensive detachable temporary fastening device which may be installed in a very small fraction of the time required for installation of the usual tape strips and which, when installed, securely fastens the doors, drawers, and other panels against outward movement, yet which may be detached and removed easily.

The device comprises essentially an element having a portion adapted to be fastened to a part within a cabinet and having a metal portion arranged, when the element is so fastened, to extend outwardly of the cabinet alongside of an edge of, and outwardly beyond the outer face of, a door or drawer front to be secured, and a relatively stiff washer having aperture means therethrough through which said outwardly extending portion is receivable so as to extend outwardly beyond the outer face of the washer when the washer is pressed firmly against the outer face of the door, drawer or panel to be secured, the outwardly extending portion being deformable at the outer face of the washer and operative while so deformed to lock the washer against withdrawal from the element.

The specific objects and advantages of the present invention will become apparent from the following description wherein reference is made to the drawings, in which:

35 Fig. 1 is an enlarged perspective view of the elements comprising the fastening device, showing them in aligned position for assembly with respect to each other;

40 Fig. 2 is a front elevation of a domestic gas cooking range with two of the fastening devices installed, one for retaining two oven doors in position and one for retaining two drawers in closed position;

45 Fig. 3 is an enlarged fragmentary sectional view of a portion of the range and of the fastening device and is taken on line 3—3 of Fig 1;

Fig. 4 is a sectional view similar to Fig. 3 illustrating a modified form of the device; and,

50 Fig. 5 is an enlarged sectional view similar to Fig. 3 illustrating another modification of the device.

Referring to Figs. 1 through 3 of the drawings, the device comprises essentially a fastening element, indicated generally at 1, which is adapted for connection to a part on the inside of a cabinet structure and a washer 2 adapted for cooperation with the element 1 for engaging the outer face of the panel or panels to be secured in place. A suitable cushioning pad 3 is pro-

vided, either separately or affixed to that face of the washer which is to be exposed toward the panel secured by the washer.

The element 1 preferably comprises a flat strip of steel having suitable means at its inner end for securing it to a part on the inside of a cabinet structure. In the form illustrated in Figs. 1 through 3, this means may comprise a hook portion 4 integral with the inner end of the element. The outer end of the element 1 is bifurcated to provide a pair of substantially coplanar flat prongs 5 which preferably are spaced apart edgewise from each other. The prongs are preferably of such thickness and of sufficiently soft steel that they can readily be bent flatwise at an abrupt angle to their normal plane, or otherwise deformed, by hand pressure, for the purposes hereinafter set forth.

On its outer face at its central portion the washer 2 is provided with a pair of small generally globular bumps 6 which may be spaced from each other and are positioned to be aligned with the prongs 5, respectively, when the washer is in position for mounting on the prongs 5. The washer also has aperture means, such as the apertures 7, arranged preferably one in each bump 6 near the central portion or peak thereof. Each aperture is shaped to receive a prong 5 endwise with slight clearance. The bumps 6 preferably are formed by stamping and distorting the metal of the washer out of its normal plane thus leaving a concavity on the face opposite the bumps for guiding the ends of the prongs 5 into the apertures 7. The pad 3 may or may not be perforated. It may be omitted in those instances in which the surface of the panel to be secured is such that slight rubbing of the washer thereagainst would not unduly mar the surface; for example, in case of unfinished surfaces. The pad preferably is composed of a plurality of laminations of very soft paper and, as mentioned, may be secured to and form part of the washer or made separately therefrom. Insofar as operation is concerned, even with the pad inserted between the washer and panel, the washer can be said to engage the outer face of the panel.

In Figs. 1 through 3 the fastening device is shown installed on a domestic gas range 8, having front panels 9 and 10 in the form of downwardly swinging oven doors and front panels 11 and 12 in the form of front walls of forwardly sliding drawers. In such range structures there is usually provided between the oven compartments and between the drawer compartments an upright frame member comprising two sheets of metal 13 and 14, respectively, which extend forwardly and rearwardly of the range and form the side walls of the adjacent ovens or drawer compartments. Suitable insulating material 15 is interposed between the sheets of metal 13 and 14. Usually a front cap 16 in the form of a strip of angular cross section is secured by suitable screws and the like to one of the sheets, for example, the sheet 13 in the form illustrated, and forms a front wall of the resultant frame member. Likewise one of the sheets, such as the sheet 14, has a flange at its forward edge against the outer face of which the free margin of the sheet 16 is juxtaposed. An intermediate portion of the element 1, indicated at 17, between the hook portion 4 and the outwardly extending portion is of such length that when the hook portion is hooked under the free margin of the cap 16, as illustrated in Fig. 3, the portion 17 lies against the forward face of the resultant frame member and the

prongs extend forwardly therefrom midway between the doors 9 and 10. With the intermediate portion 17 and the prongs 5 of the device in this position and the doors 9 and 10 closed, the washer 2, positioned with the apertures 7 in alignment with the prongs 5, respectively, and with the padding 3, if separate from the washer, between the washer and the doors, is forced onto the prongs 5 and firmly into operative engagement with the outer faces of the doors 9 and 10. While the washer is held firmly in this position, the prongs 5 are deformed so as to prevent withdrawal of the prongs from the washer, preferably by bending them flatwise in opposite directions from each other by hand pressure. Due to the bumps 6 the prongs 5 can be bent back toward the washer so that the bent over ends thereof make an angle of less than 90° with the portion of the prongs lying between the doors 9 and 10 and the free ends engage and bear firmly against the washer outwardly from its midportion. The resilient engagement of the hook portion 4 with the free margin of the sheet 16 holds the device securely in place vertically of the frame member of the range. The hook portion preferably is of a greater length than the distance between the face of the prongs 5 and the adjacent edge of the door 10, so that the hook portion 4, even though the device should shift laterally of the frame member, could not become disengaged from the sheet 16.

It should be noted in Fig. 3 the thickness of the metal of the device has been exaggerated slightly for convenience in illustration. By virtue of the abrupt bend in the prongs 5 over the bumps 6, the prongs 5 are drawn firmly against the outer face of the washer adjacent the apertures 7 so that no movement of the washer forwardly and rearwardly of the range is permitted. In the form illustrated, no part of the fastening device is interposed between the inner face of the door 9 and the front face of the frame member of the range and consequently the door 9 can swing inwardly slightly farther than the door 10. However, when forced firmly toward both doors, the washer tilts so as to firmly engage the outer faces of both doors and the prongs retain it in tilted position in firm contact with the outer faces of both of the closed doors.

In Fig. 1, one of the fastening devices is shown securing the two oven doors 9 and 10 and another one is shown securing the drawer fronts 11 and 12. If desired, however, a single one of the devices can be installed at the adjacent corners of the doors 9 and 10 and drawer fronts 11 and 12 and thus secure all four in place.

To detach the fastening device, the prongs 5 are bent back to their original position by hand, the washer removed, and the doors and the element 1 unhooked.

In Fig. 4 the device is illustrated for use with a gas range having a slightly different frame member between the doors and drawers. As there illustrated, the frame member comprises two sheets of metal 18 spaced apart and extending forwardly and rearwardly of the range and forming the walls of the adjacent compartment, suitable insulation 19 being interposed therebetween. The front of the frame member is provided by a channel-shaped strip of metal 20 the sides of which overlap the outer surfaces of the forward margins of the sheets 18. In this form of the invention, the fastening device is identical with that shown in Fig. 1 except that the intermediate portion of the element which engages the

front face of the frame of the range, has an extension 21 which extends rearwardly along the side of the range frame member, a hook 22 being provided on the extension to hook between the one of the sheets 18 and a side of the channel 20. The structure of the device is in all other respects the same as that heretofore described and requires no further description.

Referring next to Fig. 5, a form of the device suitable for holding cabinet doors or panels which do not have any stops conveniently located at the closing edges of the panels is shown. In this form, the intermediate portion 23 corresponding to the portion 17 of the device illustrated in Figs. 1 through 3, is provided with an inner extension 24 which may extend in any position so as to engage a structural member, such as the frame member 25 of the cabinet inside of the cabinet, the inner extension 24 being provided with any suitable fastening means such, for example, as a hole 26 through which a suitable screw 27 or other fastening means is passed and secured to the post 25 for securing the fastening element in fixed position to a member inside of the cabinet. The other parts of the device are identical with those heretofore described, and secured to the doors 23 in like manner.

Obviously the specific shape of the device may be modified to meet all conditions that are apt to be encountered in various cabinet structures. For example, in Fig. 5, if no frame member 25 were positioned between the doors, the inner extension 24 could be twisted or bent so that it could be secured to the top wall or bottom wall of the cabinet.

Having thus described my invention, I claim:

1. A detachable fastening device for holding in closed position a pair of spaced front panels of a domestic gas range of the type in which the inner faces of adjacent upright margins of the front panels are juxtaposed against the forward face of an upright frame member of the range when the panels are closed, and comprising a metal strip having at one end a fastening portion adapted to be detachably secured to said frame of the range rearwardly from the panels, an intermediate relatively thin portion connected at one end to the fastening portion and adapted to lie between, and in juxtaposition with, one of said inner faces and said forward face when the fastening portion is so secured, a pronged forward portion extending from the other end of the intermediate portion and adapted to lie between the adjacent upright edges of the panels and including prongs adapted to extend forwardly beyond the outer face of the panels when the intermediate portion is so juxtaposed, cushioning means having passage means therein through which the forward portion extends for supporting the cushioning means on said forward portion, said cushioning means being adapted to overlap the front faces of said adjacent upright margins of the panels when so supported, a generally flat stiff washer engageable in face to face relation with the cushioning means and having aperture means therein through which the prongs are received endwise and in which they are accommodated, said washer being adapted to overlap said adjacent margins when it accommodates the prongs, and said prongs extending forwardly beyond the washer and being bendable by hand back toward the forward face of the washer across edge portions of the aperture

means for holding the cushioning means in clamping engagement with said panels.

2. A detachable fastening device according to claim 1 characterized in that the fastening portion is in the form of a U-shaped hook adapted to accommodate snugly flatwise between its arms a thin sheet of metal.

3. A detachable fastening device for holding in closed position a pair of spaced front panels of a domestic gas range of the type in which the inner faces of adjacent upright margins of the front panels are juxtaposed against the forward face of an upright frame member of the range when the panels are closed, and comprising a metal strip having at one end a fastening portion adapted to be detachably secured to said frame of the range rearwardly from the panels, an intermediate relatively thin portion connected at one end to the fastening portion and adapted to lie between, and in juxtaposition with, one of said inner faces and said forward face when the fastening portion is so secured, a pronged forward portion extending from the other end of the intermediate portion and adapted to lie between the adjacent upright edges of the panels and including prongs adapted to extend forwardly beyond the outer face of the panels when the intermediate portion is so juxtaposed, cushioning means having passage means therein through which the forward portion extends for supporting the cushioning means on said forward portion, said cushioning means being adapted to overlap the front faces of said adjacent upright margins of the panels when so supported, a generally flat stiff washer engageable in face to face relation with the cushioning means, said washer having relatively small raised portions on its forward face and having aperture means in the crests of said raised portions through which the prongs are received and in which the prongs are accommodated, said washer being adapted to overlap said adjacent margins when it accommodates the prongs, and said prongs extending forwardly beyond the washer and being bendable by hand back toward the forward face of the washer across edge portions of the aperture means for holding the cushioning means in clamping engagement with said panels.

4. A detachable fastening device according to claim 3 characterized in that said aperture means comprise separate apertures respective to the prongs and in that said prongs fit the apertures, respectively, with small operating clearances.

5. A detachable fastening device according to claim 3 characterized in that said raised portions of the washer are in the form of separate relatively small bulges on its forward face, respective to the prongs, and the aperture means comprises apertures respective to the bulges and each fitting one of the prongs with small operating clearance.

6. A detachable fastening device according to claim 5 characterized in that the washer has concavities on its rearward face aligned with the bulges, respectively.

EMMETT F. KENNEDY.
